GAS BURNER

Harry E. Kerr, Cleveland, Ohio, assignor to The
Barber Gas Burner Company, Cleveland,
Ohio

Application July 20, 1932. Serial No. 623,471

2 Claims. (Cl. 158—116)

My invention relates to an improvement in pilot lights for gas burners and my general object is to provide a pilot light embodying a main body and a burner tip mounted on said body and provided with a plurality of outlet openings grouped in a particular way around the axis of said tip to gain maximum heating effects without causing malfunction in mixing and burning operations at any of the outlets of the tip. The pilot light is effectively used in combination with a so called jet burner, all substantially as shown and described herein and more particularly pointed out in the appended claims.

15 In the drawing accompanying this application:

Figure 1 is a sectional view through a jet burner showing a pilot light according to the invention supported thereby, which pilot light is utilized for automatically controlling the flow of gas to said burner;

Figure 2 is an enlarged sectional view of the pilot light with its burner tip shown in elevation;

25 Figure 3 is an enlarged sectional view through the burner tip of the pilot light; and

Figure 4 is a bottom view of the said tip.

Referring more particularly to the drawing the hollow cast burner body or manifold A comprises top and bottom walls 1 and 2 and side wall 3 respectively. A body A embodies a gas chamber 4 and a feed channel 5 communicating therewith through opening 6 in the bottom wall of said chamber. The top wall 1 of body A is provided with a series of protuberances or raised portions 7, uniformly spaced with respect to each other. These protuberances are perforated for communication with the gas chamber 4 and carry at their top portions a series of 35 commingling tubes or jets 8, preferably made of brass and surmounted by caps 9 of rounded or ball-shape and provided with relatively narrow intersecting slots 10, sawed at right angles across the top and downwardly into the side 45 walls of the cap.

The top wall of burner body A is formed with a centrally disposed threaded opening 12 in which a threaded apertured guide unit 14 is screwed. An elongated valve plunger 15 extends through the guide unit 14 in axial alignment with opening 6 in bottom wall 1 for control of gas fed from channel 5 into gas chamber 4 and thence to and through jets 8.

Movement of valve plunger 15 is thermos statically controlled through the medium of a

horizontally disposed compensating spring extension 17, secured at its outer end to a bi-metal bar or member 18, and engaging an annular groove 19 in the upper end of the valve with its bifurcated end. The bar 18 is connected to the vertical arm 20 of a bracket 21, which bracket is preferably an integral part of the main burner A, any suitable fastener such as a screw 22 being employed to secure bar 18 in place on the bracket arm. The supporting bracket 21 has 60 a horizontally disposed arm 23 which is formed with a round enlargement 24 centrally apertured as at 25 to snugly receive a pilot light 26. The lower end of the pilot light is connected by suitable piping 27 to the main gas supply, 70 not shown, and the upper end of the pilot jet is positioned directly beneath and in line with the bi-metal bar 18. A deflector or shield 28 protects bar 18 from the direct effect of the flame by deflecting the flame laterally and 75 thence upwardly around and out of contact with the bar. The deflector is formed at its outer end with a flat portion 29 which is secured to the supporting bracket 21 by means of the screw 22, which screw also serves to attach the 80 bar 18 in place.

A guard plate 30 directs the flame of the pilot jet 26 upwardly toward the tips of burner jets or tubes 8.

Pilot light 26 embodies a commingling tube or 85 jet 31 preferably of brass, which tube is surrounded by a separate hollow burner tip 32, preferably made of fire clay or other unburnable material. The bottom end of commingling tube 31 is screw threaded, as at 33 for attachment to 90 piping 27 and has a cupped entrance 34 extending into a small discharge orifice 35 for gas. Air intake ports 36 extend through the side walls of the jet into a central main passage 37. The top of burner tip 32 is enlarged and rounded or ball-shaped as at 38, and extends laterally slightly beyond and in overhanging relation with respect to the circumferential side wall of hollow neck portion 39 of said tip, and a rounded 95 groove or channel 40 is circumferentially arranged between the enlarged top 38 and neck portion 39. Groove 40 thus separates said top and neck portions, and the said top portion forms a dome-shaped covering or head for the groove. Neck portion 39 is hollow thus providing a rounded mixing chamber 41 for gas entering therewith from main passage 37, and a series of symmetrically arranged upwardly and outwardly inclined passages 42 formed partially in the upper extremity of hollow neck portion 39 100 105 110

and partially in the solid head portion 38, connect chamber 41 with rounded channel or groove 40. The upper walls of inclined passages 42 merge with the upper outwardly curved portion 5 of the wall of channel 40 and cooperate with the latter to guide the gas emitting through said passages laterally on a sweeping curve to eliminate turbulence in and cause a lateral spreading of the gas flame. As passages 42 extend 10 through the inner wall of chamber 41 from a point close to the top thereof, they assist in directing the flow of gas from said chamber without danger of forming undesirable gas or air cushions, which would tend to cut down the flow 15 of gas through the pilot jet and lessen the efficiency of the pilot jet.

Having thus described my invention, what I claim is:

1. A pilot light for gas burners including a 20 tubular gas and air commingling tube, and an integral burner tip member seated upon the upper end of said tube, said tip member having a neck portion extended into said tube and embodying a rounded chamber open at its bottom, a dome-shaped head portion laterally extended beyond the circumferential wall of said neck portion, a connecting portion between said

head portion and neck portion including an annular groove making the cross section of said connection smaller than the cross section of said neck portion, a series of upwardly inclined narrow passages between said chamber and said annular groove terminating below and adjacent to the bottom face of said head portion to promote baffling and spreading of the gas and air streams emitted through said passages.

2. A pilot light for gas burners including a tubular gas and air commingling tube, and a burner tip member seated upon the upper end of said tube, said tip member including a neck portion extended into said tube and embodying a rounded chamber open at its bottom, a dome-shaped head portion laterally extended beyond the circumferential wall of said neck portion, a connecting portion between said head portion and said neck portion including an annular channel and a series of upwardly inclined narrow passages between said chamber and said channel terminating within said annular channel in alignment with the upper wall thereof to promote baffling and sweeping spreading of the gas and air streams emitted through said passages.

HARRY E. KERR.
